UNITED STATES PATENT OFFICE.

GEORGE H. HAMILTON AND FRED J. BLAKSLEE, OF GRAND RAPIDS, MICHIGAN, ASSIGNORS TO AMERICAN SEATING COMPANY, OF GRAND RAPIDS, MICHIGAN, A CORPORATION OF NEW JERSEY.

CHAIR.

Application filed January 23, 1922. Serial No. 531,135.

To all whom it may concern:

Be it known that we, GEORGE H. HAMILTON and FRED J. BLAKSLEE, citizens of the United States, residing at Grand Rapids, in the county of Kent and State of Michigan, have invented new and useful Improvements in Chairs, of which the following is a specification.

The present invention relates to chairs; and its object is to provide improved means for connecting the backs of chairs side by side to form rows or ranks of chairs, as adapted for use in theatres, auditoriums and the like.

This object is attained by, and the invention finds preferable embodiment in, the structure hereinafter particularly described and illustrated by the accompanying drawings, in which:

Figure 1 is a side view of the standard or support for an adjacent pair of chairs, illustrating particularly the means whereby their backs are connected, the position of the chair backs however being shown merely in dotted lines for the sake of clearness;

Figure 2 is a front view of a portion thereof;

Figure 3 is a rear view of the same;

Figure 4 is a transverse sectional view thereof taken on a plane corresponding to either line 4—4 of Figure 1; and

Figure 5 is a view in perspective showing a modified construction of a clamping member.

In the embodiment of the invention chosen for illustration by the drawings and for detailed description in the body of this specification, a pair of adjacent chairs in a connected row or rank thereof are shown.

These adjacent chairs, having backs 1, 2 whose front surfaces are concave and whose rear surfaces are convex in horizontal cross section, and having seats of any desired form as indicated at 3, are connected by

upwardly extending standards or supports 4, preferably of cast metal, having base portions 5 and arm portions 6. These supports have a central body portion 7 intermediate the mutually adjacent edges of the chair backs and contacting said edges in the construction seen in Figure 4, and laterally extending oppositely disposed ribs 8. A clamp member 9 having a concave inner surface 10, spaced from the front surface of the chair

backs, and lateral edges 11 contacting said front surfaces adjacent their said edges respectively, as particularly shown in Figure 4, is clamped to the support by threaded means—the screw bolts 12 passing through spaced apart orifices 13 in the clamp member and threaded in to the nut in the body portion 7 of the support. The chair backs are thus clamped in position between the clamp member 9 and the ribs 8, and to more securely thus hold them the support's ribs 65 may be provided with spurs 14 and the clamp member with like spurs 15 forced into the backs by screwing down the bolts. These bolts 12 are turned by their heads 16 which project from the front of the structure. Instead of forming the clamp member of cast metal as indicated particularly in Figures 1 and 4, it may be made flexible (as by stamping it from sheet metal) and formed as indicated in the clamp member 9¹ shown 75 in Figure 5; and its edges 11¹ intermediate its orifices 13¹ may be spaced as shown in that view from the front surfaces of the chair backs. By such provision, a secure clamping contact of the clamp member on 80 the chair backs in the region of the bolts 12¹ is attained.

It will be seen that inasmuch as the chair backs are, as seen in Figure 4, concavo-convex in horizontal cross section at their clamped 85 edge portions, the adjacent chairs are more securely held against separating movement in the direction in which the row or rank of connected chairs extends, than if such clamped portions extended in a direction 90 parallel with that in which the rank or row of chairs extends.

The invention being intended to be pointed out in the claims, is not to be limited to or by details of construction of the particular 95 embodiment thereof illustrated by the drawings or hereinbefore described.

We claim:

1. In a structure of the character described; an upwardly extending support 100 having a body portion intermediate the mutually adjacent edges of the chair backs hereafter mentioned, and having laterally extending ribs; a pair of chair backs whose front surfaces are concave and rear surfaces convex in horizontal cross section; a clamp member; threaded means extending between the clamp member and the support's body 105

portion for clamping them together with the mutually adjacent edge portions of the chair backs between the clamp member and said ribs.

5. 2. In a structure of the character described; an upwardly extending support having a body portion intermediate the mutually adjacent edges of the chair backs hereinafter mentioned, and having laterally 10 extending ribs; a pair of chair backs whose front surfaces are concave and rear surfaces convex in horizontal cross section; a clamp member having a concave inner surface spaced from the chair backs and lateral 15 edges contacting the front surfaces of the chair backs adjacent their said edges respectively; threaded means extending between the clamp member and the support's body portion for clamping them together 20 with the mutually adjacent edge portions of the chair backs between the clamp member and said ribs.

3. In a structure of the character described; an upwardly extending support having a body portion intermediate the mutually adjacent edges of the chair backs hereinafter mentioned, and having laterally 25 extending ribs; a pair of chair backs whose front surfaces are concave and rear surfaces convex in horizontal cross section; a clamp member disposed parallelly to the support and having spaced apart orifices and having its inner surface spaced from the chair backs 30 intermediate said orifices; threaded means extending between the clamp member and the support's body portion and passing through said orifices for clamping the clamp member and the support together with the mutually adjacent edge portions of the chair 35 backs between the clamp member and said ribs.

backs between the clamp member and said 40 ribs.

4. In a structure of the character described; an upwardly extending support having a body portion intermediate the mutually adjacent edges of the chair backs 45 hereinafter mentioned, and having laterally extending ribs; a pair of chair backs whose front surfaces are concave and rear surfaces convex in horizontal cross section; a flexible clamp member disposed parallelly to the 50 support and having spaced apart orifices; threaded means extending between the clamp member and the support's body portion and passing through said orifices for clamping the clamp member and the support together 55 with the mutually adjacent edge portions of the chair backs between the clamp member and said ribs.

5. In a structure of the character described; an upwardly extending support 60 having a body portion intermediate and contacting the mutually adjacent edges of the chair backs hereinafter mentioned, and having laterally extending ribs; a pair of chair backs whose front surfaces are concave 65 and rear surfaces convex in horizontal cross section; a clamp member; threaded means extending between the clamp member and the support's body portion for clamping them together 70 with the mutually adjacent edge portions of the chair backs between the clamp member and said ribs.

In testimony whereof we have hereunto set our hands at Grand Rapids, Michigan, this 6th day of January, 1922.

GEORGE H. HAMILTON.
FRED J. BLAKSLEE.
